(57) **CLAIM**

The ornamental design for a 5 valve port pipe by flange manifold, as shown and described.

DESCRIPTION

FIG. 1 is a perspective view of a 5 valve port pipe by flange manifold;

FIG. 2 is a top view thereof;

FIG. 3 is a bottom view thereof;

FIG. 4 is a rear view thereof;

FIG. 5 is a front view thereof; and,

FIG. 6 is a right-side view thereof, the left-side view is a mirror image thereof.

The broken line showing of portions of a 5 valve port pipe by flange manifold is included for the purpose of illustrating environmental structure and forms no part of the claimed design.
